HORACE D. MUNDAY, OF SCHENECTADY, NEW YORK

TRUING APPARATUS

Application filed July 26, 1929. Serial No. 381,178.

This invention relates to methods of and apparatus for grinding and particularly to methods and devices for grinding or truing commutators or collector rings of electric machines.

It is the present practice to grind commutators or collector rings by means of a motor-driven abrasive wheel mounted on a cross feed slide carried by a carriage which in turn is mounted on a pair of ways parallel to the commutator, means being provided to give the abrasive wheel an axial movement relative to the commutator. One disadvantage of the present practice, as carried out by the device just described as well as similar devices now in use, is that the attention of the operator is required throughout the grinding operation. Another disadvantage of this practice is that, generally, it is necessary to remove some of the brush holders or other parts of the machine in order to permit the entrance of the grinding wheel into contact with the commutator. Furthermore, during the grinding operation it is the general practice to take off all or some of the useful load of the electric machine. Also, the grinding operation as now performed consumes a considerable time and as a result it is not usually performed as often as it should be.

By the use of the preferred forms of the present invention I avoid the disadvantages incident to present practice as above noted. My improved grinding device is automatic and requires little or no attention during actual operation. In using many forms of my invention it is unnecessary to remove any of the brush holder or other parts of the machine, and it is also unnecessary to take off any of the useful load from the machine.

A further important advantage of the devices constructed in accordance with the present invention is their adaptability to the truing of commutators having ridges or ruts as well as greater effectiveness in truing such commutators. When a commutator is ground by an abrasive block which is fed forward toward the commutator in a general radial direction, there is very little more grinding of the ridges of the commutator than the ruts or other "low" parts of the com-

mutator. When the abrasive is first brought into contact with the commutator it contacts with the ridges only and for a short time the ridges are ground down to the exclusion of the remaining parts of the commutator. This condition, however, is of very short duration because the ridges quickly wear a groove in the surface of the abrasive and further advance of the abrasive results in contact of the abrasive with the "low" parts of the commutator surface. Thereafter the low parts are ground down as fast as the ridges, and continued grinding has no further effect in reducing the ridges.

By the present invention I avoid the disadvantages just noted and provide a grinding device which will serve to grind down the ridges continually until they are eliminated.

Numerous objects and advantages of my invention other than those above mentioned will be apparent from the following description taken in connection with the accompanying drawings wherein, Figure 1 is a fragmentary side elevation of a commutator and brush holder and one form of my improved commutator truing means.

Figure 2 is a perspective view of one of the parts shown in Figure 1.

Figure 3 is a view similar to Figure 1 but showing a modified form of truing device.

Figure 4 is a sectional view of a brush holder and associated therewith a modified form of truing means.

Figures 5 and 6 are front and side views respectively of a brush holder and associated therewith a still further modified form of truing means.

Figure 7 is a view similar to Figure 6 but showing a further modification.

Figure 8 is a view similar to Figure 6 but showing a yet further modification.

Figure 9 is a view similar to Figure 4, but showing a further modification.

Figure 10 is a sectional view showing another modification.

Figure 11 shows in side elevation a commutator surrounded by a brush holder ring and associated with such commutator a further modified commutator truing device.

Figure 12 is a view of the structure shown

in Figure 11 looking toward the end of the commutator certain of the parts being shown in section.

25 Figure 18 is a fragmentary plan view of the structure shown in Figure 17.

30 In the forms of invention herewith illustrated, I employ preferably as a truing or abrading means, an abrasive ribbon or strip such as a strip of sand paper and associated with such strip is a suitably supported pressure member adapted to engage the strip and press the same against the high spots of the commutator. Also in the forms of 35 invention herein illustrated, I preferably provide some means for feeding the abrasive strip between the pressure member and the commutator or other part, which it is desired to true, so that fresh or unworn abrasive surfaces may be brought into contact with the commutator as desired.

40 A number of different means may be employed for feeding the abrasive ribbon. When the ribbon is drawn against the rotation of the commutator, I may if desired, employ for this purpose a small motor with speed reducing gear connected to a reel on which the abrasive ribbon is wound. If the abrasive ribbon moves with the rotation of 45 the commutator, such a motor may if desired be omitted and reliance had on the friction of the commutator to draw the abrasive ribbon along. In the latter case I often find it advisable to provide some means for hindering the movement of the abrasive strip, such for example as a clock escapement mechanism for hindering the rotation of the wheel, which carries the ribbon. If the commutator is on an electric machine which runs 50 in both directions, a small motor should be used to wind up one end of the ribbon while the unwinding of the ribbon on the other roll is hindered by the clock escapement or 55 other delaying means. Torque-limiting means, such a resistance in the armature circuit of motor 214, may be used to limit the pull of the motor to an amount that will not pull in two the abrasive strip. In this 60 way the motor serves the purpose of a spring 65

with constant tension and infinite length, or of a weight with a long drop.

70 Since the abrasive ribbon is flexible, means may be provided by which the ribbon may make contact with the commutator over a considerable peripheral span, thus for this purpose the pressure member may have its active end formed as an arc conforming to that of the commutator.

75 The pressure member may press steadily or differentially or with delayed action. Where there are no flat spots in the commutator, it being desired to grind only ridges, a steady pressure may be used. If it is desired to grind out flat spots, a differential 80 pressure or delayed action pressure may be employed, or a positive or non-reversible feed may be used, or such a feed may be used in conjunction with means for delaying the 85 advancement or forward movement of the abrasive or its tangential movement toward the commutator.

90 The principles underlying the operation of the various forms of my invention herein disclosed will be particularly pointed out in connection with the specific descriptions of 95 these forms. While my improved truing means is particularly adapted for truing commutators and slip rings, it will be understood that such means may be applied to the 100 truing of shafts, rolls and similar bodies which it is desired to cut to true, round or cylindrical shape.

105 Figures 1 and 2 show one form of my invention. The abrasive member or sand paper ribbon 21 is unwound from a reel 22 and passes thence under some or all of a set of brush holders 23, from which the brushes have been removed and wooden or other blocks of the same dimensions substituted. 110 In this form of my invention each block is divided into two parts of wedge shape designated respectively by the reference characters 24 and 25. By employing blocks of this form, a differential pressure of the abrasive ribbon 115 against the commutator 26 is given by the block when advanced by the pressure finger 27 of the brush holder, that is, less pressure will be required to stop the advance of the block into the low spot of the commutator than will be required by the high spot of the commutator to shove the wooden block backward.

120 This is due to the friction between the wedges 24 and 25 and the sides of the brush-holder box. Such friction resists all motion of the wedges, either toward or away from the commutator. When a low spot of the commutator passes under the brush holder, the spring moves the wedges through the box 125 toward the commutator until the strip 21 is pressed against the commutator surface. As it is apparent that the friction above mentioned is opposing the action of the spring 130 27, the pressure of the strip on the com-

mutator at the low spot will be the difference between the force of the spring and opposing friction. In other words the pressure of the strip on the low spot will be considerably less than the force of the spring 27. On the other hand when a high spot comes under the brush holder and as a result the strip and the wedges are pushed back, the force which must be exerted by the commutator to cause this backward movement, must be one which will overcome the friction of the wedges against the brush holder box and in addition it must overcome the pressure of the spring 27. In other words, the pressure between the abrasive strip and the commutator as a high spot of the commutator is coming under the brush-holder, is considerably greater than the pressure of the spring. The result therefore of the use of the wedges 24 and 25 is to cause greater abrasion of the high spots than the low spots and because of this differential pressure effect, the high spots located circumferentially of the commutator in line with the low spots will be eliminated. It is to be noted that the use of wedges create a resistance to the motion of the pressure finger, which resistance may be described as of a passive character, that is, while resisting motion in one direction it does not correspondingly assist motion in the opposite direction. By employing a resistance of this character I am able to produce the differential abrading effect which trues the commutator. To consolidate or unify the pressure of the individual blocks located in successive brush holders in line with one another, I may provide a trough or U shaped member 29 made of horn fiber or leatheroid paper about $\frac{1}{16}$ or $\frac{3}{32}$ inch thick. This trough is slipped under the brush holder boxes 31 and loosely laced thereto by cords 32 passing through holes 33 in the sides of the trough and over the tops of the brush holder boxes. The friction of the commutator 26 rotating as indicated by the arrow 28, draws the abrasive ribbon from the reel 22 under the trough 29. The wooden blocks bear against the hollow part of the trough and force the trough against the abrasive ribbon and the ribbon against the commutator with the differential pressure that will grind out the flat spots. To permit a slow motion only, of the reel 22, the gear 41 on the shaft of the reel may be belted by a chain belt 42 to the gear 43 driving the clock escapement mechanism 44, the speed being changed by adjustment of the weights 45 on the escapement arm 46. Instead of the wooden block being cut into parts, a solid block may be employed and smeared with asphalt to give a delayed action. Or if desired a divided block such as is shown in Figure 1, may be used together with asphalt. Or if desired, the brushes may be left in the brush holders and used without any friction or asphalt added as hindering means, bearing on the trough 29 or directly on the abrasive ribbon without the use of the trough. Such a construction could advantageously be used to eliminate ridges in the commutator; also flat spots if there is considerable brush friction or other means of resisting brush movement. When there is a tendency to chatter, I may if desired, secure the trough 29 or an equivalent spacer such as a flat non-stretchable sheet form of material, against side or tangential movement, as for example by tying the trough to some stationary part of the machine other than the brush-holder by a cord which may advantageously be passed through the side holes 33 of the trough.

Figure 3 shows how a ridge 51 and a commutator 52 may be ground down by means of a sand paper ribbon 53. Swivelled at 54 is a timber 55 having a block or step 56 hollowed out at the top over which top is stretched the canvas or leather strip 57 secured at its ends by the screws 58, such canvas strip pressing the sand paper ribbon over a considerable peripheral span against the commutator 52. The weight 61 on the lever 62 on the fulcrum 63 raises one end of the timber 55 and presses the sand paper ribbon against the commutator 52. The speed of passage of the sand paper ribbon may be controlled by the clock escapement mechanism 64 geared to the reel 65. The commutator rotates in the direction of the arrow 66. If it is desired to grind out a flat spot in the commutator, the canvas strip 57 may be omitted, the wooden block or step pressing the sand paper ribbon against the commutator. In this case the timber 55, may be raised with a differential pressure or with delayed action, or it may be raised positively, that is non-reversibly or it may be raised positively and with delayed action. Pressure members operating on other principles may be employed for truing the commutator or other cylindrical member. I may if desired clamp the pressure member to the brush holder box or provide some means whereby its retrograde movement is limited and in this case depend upon structural rigidity of the brush holder to exert more pressure on the high spots than on the low spots of the commutator. While parts of the brush holder, such as the brush holder box are usually regarded as fixed supports or strength members these parts are adapted to yield slightly when subjected to the upward thrust caused by a high part of the commutator coming under the abrasive and as a result the brush holder causes the abrasive to exert a very strong pressure on the high part, thus abrading the high part rapidly. I may also if desired, provide means by which the advancement of the pressure member toward the commutator may be definite-

ly limited so that the abrasive strip will not touch or will just skim the flat spots, and when such a limiting means is employed, I may maintain the pressure member in its most advanced position by the usual brush holder finger employed for advancing the brush through the brush holder. With such a construction it is clear that the brush holder finger may be made to exert its full pressure on the high spots and none or little on the low spots of the commutator. Or if desired, the pressure member may be merely a brush mounted in a brush holder, so constructed or arranged as to provide for considerable friction of the brush in the brush holder box or where there is a weight added to the brush holder finger to exert a strong pressure against backward movement of the brush. Delayed action hindering means may be used to delay the advance of the pressure member into the flat spots of the commutator, thus confining the abrading effect to the high spots of the commutator. An example of such delay action hindering means is the asphalt above mentioned. It is obvious that structures other than brush holders may be used as supports for the pressure members to press the sand paper ribbon against the high parts of the commutator. One advantage of the use of brush holders as supports for the pressure members when the truing operation is performed while the electric machine is in operation, is that the brush holders are generally located at neutral points of the commutator and any tendency to short circuit the commutator bars by reason of the abrasive picking up copper is minimized.

Figures 4 to 18, inclusive, illustrate other embodiments of my invention employing one or another of principles of operation above mentioned.

In the construction shown in Figure 4, I provide a means for limiting the backward movement of the abrasive away from the commutator, any backward movement in excess of the adjusted limit requiring distortion or structural yielding of the brush holder and connected parts. In this figure I make use of an iron strap 80 formed with a foot 82 and hinged at 83 to a block 84 in which is mounted the temper screw 85 and a thumb screw 86 which serves to secure to the block 84 a metal strap 87. Strap 87 is provided at its lower end with a foot 88, the foot 88 and the foot 82 being positioned beneath the walls of the brush holder box. The strap 87 is slotted to the point 89 to permit adjustment of the strap 87 to fit a brush-holder box with an inclined inner end.

In assembling the device shown in Figure 4, the two sheet metal straps are inserted through the brush-holder box, the block 84 being then thrown back on its hinge and the pressure member 91 inserted. The strap 87 is then secured to the block 84 and the tem-

per screw 85 adjusted to give the desired amount of pressure on the sand paper from the yielding brush holder structure.

I find that in certain cases it may be desirable to limit the forward motion of the pressure member, so as to prevent the abrasive from being pressed against the flat spot of the commutator. In the device shown in Figures 5 and 6, I provide a means for limiting the advance of the pressure members instead of limiting the backward movement as is the case in Figure 4. In Figures 5 and 6 I provide a pressure member 101 which may be formed as a solid block of wood or fiber, or may, be divided into wedge shaped parts as indicated by the dotted line 102' in Figure 6. At the top and on either side of the pressure member this member is formed with shoulders 103 which serve to support the temper screws 104 positioned near diagonally opposite corners of the pressure member 101. The ends of the temper screws 104 abut on the front and rear walls respectively of the brush holder box 106. The heads 107 of the temper screws are graduated circumferentially and these graduations are adapted to cooperate with pointers 108 extending upwardly from the shoulders 103, to indicate the adjusted position of the temper screw. The threads of the temper screws are of such pitch that variations in position of the ends of the screws may be indicated readily to within 1/1000 of an inch. The use of abutting inclined end surfaces in the wedge members in Figures 5 and 6 serves to give a lateral thrust to the two parts in opposite directions so that they frictionally engage two opposite walls of the brush-holder box. The friction is subtracted from the pressure of the pressure finger in causing the advance and is added to the pressure of the pressure finger to resist backward motion of the pressure member due to a high part of the commutator and in this manner the abrasive effect is increased over that due to the pressure finger acting alone. The wedge principle has been briefly mentioned in connection with Figure 8 and explained in more detail in connection with Figure 1.

In setting up the device shown in Figures 5 and 6 the lowest flat spot of the commutator is brought under the pressure member and the temper screws are then advanced to a point where the ends just come into contact with the walls of the brush-holder box. In this position the sand paper ribbon will just skim the flat spot; by adjustment of the screws a few thousandths of an inch a slight cut can be taken on the flat spot as for example when it is desired to thoroughly clean up the flat spot. A variation of this procedure is to adjust the screws 104 so that only the highest part of the high part will make contact with the sand paper ribbon

and then adjust the screws occasionally to allow a slight advance of the pressure member, as the highest part is worn off.

Figure 7 shows one form of my invention applied to a brush holder having a pigtail retaining screw in the front wall of the brush-holder box. In this form of my invention, I substitute for the pigtail retaining screw a thumb-screw 115 and I provide a pressure member 116 having an inclined outer end against which the thumb-screw 115 is adapted to abut. It is clear that when turning the thumb-screw to the right, the limit of retrograde movement of the member 116 is moved nearer to the commutator and by turning the thumb-screw to the left, the limit is moved to the opposite direction. By adjusting the thumb-screw in this way, just the pressure desired can be exerted by the pressure member on the high spot of the commutator and can be made sufficient to insure truing action and at the same time not great enough to tear the sandpaper. The pressure member 116 may be formed of rigid material such as wood or fiber or if desired its lower part may be formed of rubber or other yieldable material.

The pressure member 125 shown in Figure 8 has secured in it a stud 126 passing freely through a hole in a horizontal side portion of a strap 127, a vertical side portion of which is secured to the brush-holder box by the thumb-screw 128 which has been substituted for the usual pigtail retaining screw. Thumb nuts 129 above and below the horizontal top portion of the L or T-shaped strap 127 serve to limit both the forward and backward movement of the pressure member 125.

I preferably form the strap 127 of two parts 130 and 131 which are connected together by means of the screw 132 threaded into the part 130 and having jam-nuts 133 between which and the part 131 is positioned a stiff spring washer 135. The nuts 133 are adjusted so as to subject the washer 135 to considerable pressure. The washer 135 forms a relief means in case the pressure member 125 is subjected to an undesirably high pressure tending to force it upward through the brush-holder box and so prevents injury to the parts such as tearing the sandpaper, when for example the commutator has a very deep low spot or when the lower of the nuts 129 is adjusted too high on the stud 126.

The pressure member 125 may if desired be divided into two wedges as indicated by a dotted line in Figure 8 and the stud 126 threaded into one of the wedges, preferably the lower wedge. I may if desired, use the brush holder pressure finger to advance the pressure member 125 and the pressure finger in conjunction with the wedges may be employed for frictional hindering of the movement of the abrasive. It is obvious that such frictionally hindered movement may be em-

ployed with or without the means for limiting the forward or backward movement, this limiting effect depending upon the position of the thumb-nuts 129. The construction arranged as described may be used with or without the relief means depending upon whether the spring washer 135 is partially or entirely compressed and depending also on the position of the lower of the thumb-nuts 129.

By the construction shown in Figure 9 I provide a pressure member 140 which is adapted to be clamped or held rigidly in the brush-holder box. The pressure member 140 is formed of two similar parts 141 and 142 respectively. Each part is formed with a shoulder 143 on its inner face, the parts being of such form that they are spaced from one another at their upper ends as indicated at 146. Extending through the upper end of each part is a thumb screw 148 which when tightened will serve to force the lower ends of the parts outwardly against the sides of the brush-holder box and thus clamp the pressure member tightly in the box. When the screw 148 is tightened so that the pressure member is held rigidly in the box, I depend upon the structural yielding of the brush holder to resist retrograde movement of the abrasive. I may however, use the device shown in Figure 9 with the screw 148 tightened sufficiently to cause a frictional engagement between the pressure member and the sides of the brush-holder box, but not sufficient to prevent forward movement of the pressure member under action of the brush holder pressure finger 150 or other means for pressing the pressure member forward in the brush holder. With the thumb-screw 148 adjusted in this manner, the operation of the device for truing a commutator is similar to the operation of the device described in connection with Figures 1 and 2.

Figure 10 shows a construction by which a commutator can be trued by a pressure member located in a brush holder and at the same time a current collecting brush may be employed in the same brush holder, so that the electric machine may continue to function during the truing operation. This construction is particularly desirable where the machine to be trued is provided with only two or a few brush holders. Reference character 169 indicates a carbon brush and reference characters 171 and 172 respectively represent a pair of wedges constituting the pressure member. Adapted to bear near one end on the carbon brush and near its other end on the pressure member is an equalizer bar 173. The brush holder pressure finger 174 engages and presses against the bar 173. The sandpaper ribbon is drawn under the pressure member while at the same time the brush 169 which is located at one side of the sandpaper strip is free to make contact with the com-

mutator. Anchored in the lower wedge 171 is a stud 185 passing freely through a hole 186 in the upper wedge and a corresponding hole in the equalizer bar 173. One purpose of this stud is to keep the parts assembled so that they can be drawn out of the brush-holder box as a unit. Another purpose is to limit the advance of the pressure member and for this purpose I provide two nuts 190 which can be adjusted to rest on the top of the brush-holder box and limit the advance of the pressure member to contact with a part of the commutator of any elevation desired. The equalizer bar 173 can be kept substantially horizontal by adjustment of thumb-screw 191 threaded in one end.

Large electric machines are often surrounded by a brush holder ring or have a fan guard at the outer end of the commutator. 20 In truing commutators of this construction difficulty is experienced in positioning a strip of abrasive paper so as to obtain a long tangential approach of the paper to the commutator, and where a fan guard is employed 25 there is difficulty in introducing the ribbon into position where it may be properly fed beneath the pressure member.

Figures 11, 12 and 13 show a means for introducing a roll or drum 198 of sandpaper 30 under a brush holder ring 200. The sandpaper roll or drum 198 is connected to a shaft 202 which is supported and driven somewhat similarly to the shaft which drives the rear wheels of an automobile. The pin 203 in the hole in the end of the shaft 202 engages the wooden drum 198 through a notch in the end of the drum. The steel tube 204 supports the drum and encloses the shaft 202. Surrounding the part of the tube 204 near the 35 commutator is a fiber tube 205 which serves to insulate the tube 204 from contact with the live parts of the electric machine. The steel tube is held by a clamp 206, the other end of which is secured to some fixed support such 40 as the bearing cap of the electric machine, as shown for example in Figure 11. The thin insulating fiber tube 205 surrounds the inner steel tube 204 near the commutator and extends under and somewhat beyond the 45 clamp 226 by which it is held tightly to the steel tube 204. In this way no grounds can be made on the steel tube 204 except beyond the end of the fiber tube 205.

The general positioning of the drum 198 50 relative to the commutator is obtained by properly locating the clamp 206 on the tube 204 and the connection of the clamp with the bearing cap of the machine. Smaller axial adjustments of the drum may be obtained by 55 means of a hand wheel 207, the hub 208 of which threadedly engages the stud 209 anchored in the clamp 206. The hub 208 turns freely in the upper end of the clamp 211, the lower end of which is clamped tightly to the 60 tube 204. The rims 212 of the drum are fiber

so that contact of the drum with the live parts of the electric machine will do no harm. A sprocket gear 213 serves to connect the shaft 202 with the driving motor 214 through reducing gears. The winding-off drum 198a 70 is connected to a clock escapement similar to that shown in Figures 1 and 3. A hand-wheel on the motor shaft permits manual adjustment or operation.

As a means for guiding the abrasive ribbon so that it will approach the brush holder in a general tangential direction I provide a guide 220 which is supported from the tube 204 by a structure designated generally by reference character 225 and which comprises a clamp 226 which serves to clamp to the tube 204 the slotted arm 228 on which is mounted the clamp 229 adjustable along the said slots to any position on the arm 228, common bolts through the clamp 229 and the 80 slots securing at the same time the arm to the clamp and the clamp to the fibre rod 227 which is secured to the guide-supporting plate 230 by bolts 231; guide 220 is secured to the plate 230. It will be noted that the 85 clamp 229 permits adjustment of the rod 227 in a direction axial of the commutator and also permits the adjustment of the guide 220 to different angular positions with respect to the tube 204, as well as radial adjustment (along the slots) on arm 228. Slots in the plate 230 permit vertical adjustment on the fibre rod 227. The supporting structure 90 95 100 105 110 115 120 125 130 135 140 145 150 155 160 165 170 175 180 185 190 195 200 205 210 215 220 225 230 235 240 245 250 255 260 265 270 275 280 285 290 295 300 305 clamp 206, the inner end of the screw engaging a slot 234 in the tube 204. The sprocket gear is splined on the shaft to permit some axial movement without the necessity of 5 moving the motor 214.

The pressure member used in the device illustrated in Figures 11 to 18 may be of any of the types elsewhere described but I preferably employ a pressure member of the construction illustrated in Figure 8.

In the form of invention shown in Figures 14—16, the slotted strap 241 is secured to the front wall of the brush-holder box 242 by the cap-screw 243 substituted for the pig-tail retaining screw. Secured to the strap 241 by the cap-screw 244 is the block 245 vertically adjustable on the said strap. This block supports a pair of springs 249 which force the wedge 251 to the right by acting 20 on one of several pins 252 projecting from the sides of the wedge. The wedge is held in position by the walls of the slot in strap 241 and the shoe 253 integral with the lower end of rod 254 slidable in a hole in block 25. Between the shoe and the block is a stiff spring 255, the tension on which can be adjusted by means of the nuts 259. This spring serves as a relief means. Set-screw 261 in the lower end of strap 241 abuts on the 30 front wall of the brush-holder box and serves to brace the strap against movement. Set-screw 262 projects into a slot in the rod 254 and prevents it from turning.

In the form of invention shown in Figures 35 17 and 18, the pressure member is advanced towards the commutator by the cam 272, which swivels on the pin 273 mounted on a pair of notched discs 274 integrally united by the cross-bar 275, said discs and cross-bar 40 being adjustably secured by the cap-screw 276 to the strap 281, which is similar to the strap shown in Figure 16 and is similarly secured to the brush holder. The cam 272 is turned toward the left into contact with the member 45 271 by means of springs 283.

In the above described forms of my invention where dependency is had upon structural yielding or structural rigidity to obtain the desired resistance to small retrograde movement radially of the commutator, I have obtained such structural yielding by the construction of a pressure member or the structure of some part connecting the pressure member with a stationary support. It will 50 however, be understood that such yielding may be caused to occur in the abrasive strip itself by providing an abrasive strip which is compressible in a direction of its thickness. Thus if desired I may employ a fabric strip 55 secured to the back of the sandpaper strip so that the fabric of the fabric strip will serve as a spacer between the sandpaper strip and the pressure member. Such fabric strip need not in all cases be united to the sandpaper 60 strip beneath the pressure member. Where 65

the fabric strip is united to the sandpaper strip, the fabric strip will prevent tearing of the flexible abrasive strip under excessive tension.

In the operation of the truing device shown 70 in Figures 11—13, the device is mounted on the frame of the machine to be trued substantially as described, and shown in Figures 11 and 12.

The dynamo electric machine may be assumed to run in both directions, such as a motor driving steel mill rolls. In starting the operation the main portion of the sandpaper strip will have been rolled on the winding-off drum, 198a, either by disengagement of the retarding clock escapement, or, preferably before mounting on the motor frame. The free end of the sandpaper strip is then run under one or more of the brush holders mounted on one or more of the brush holder studs, and secured by any convenient means, as by a tack or two, to the winding-up drum, 198.

Pressure members, such as shown in Fig. 8, are substituted for the brushes in the brush holders under which the sandpaper strip is run, and the cooperating stationary parts 130 clamped to the brush holders. A thin fibre sheet, 232, may then be inserted between the brush holders and the sandpaper strip and the ends of the fibre sheet secured to some stationary part, such as the brush holder ring 200. The connections between the sheet and the ring should preferably be inelastic so that any to-and-fro movement of the sheet is avoided to a considerable extent. The mill motor is then started and also the small feeding motor 214.

This type of pressure device (Fig. 8) may be used in several ways, as previously described. Assume that it is used as a spacing member, thus hurdling the flat parts. The pressure member in the brush holder box is then advanced by backing off the upper thumb-nut 129 till a small to-and-fro movement of this member is felt. The lower thumb-nut 129 is then screwed tightly against the horizontal part 131. Nuts 133 may be set up till spring 135 is well compressed. The proper amount of pressure can be judged by such indications as the quiver of the brush holder or pressure member, the jerking of the abrasive strip or its tension, and by the amount of copper dust coming off. Then at each reversal of the mill motor the effect of the grinding can be observed for an instant. As long as the bottom of the lowest flat part is being just missed or skimmed, the truing is being done at the minimum copper loss.

Where the voltage may be too high for safety the part 130 may be enlarged and made of fibre, thus insulating the plate 131 and connecting parts from the brush holder. Or the adjustments can be made while the 130

machine is at rest. On large machines it is advisable to keep a jet of air playing on the commutator to drive the copper dust away from the winding, or take other means to keep it out. Now and then the pressure member is advanced by adjustment of the thumb-nuts 129 as the various signs indicate that the high parts have been reduced to some extent. The operation is continued till the 10 commutator becomes true.

This application is a continuation in part of my copending application Serial Number 278,748 filed May 18, 1928.

Having now described my invention what 15 I claim and desire to secure by Letters Patent is:

1. A commutator truing device comprising a flexible abrasive member, a brush holder having a brush guide, a pressure block positioned in said guide and adapted to advance toward the commutator, means for drawing the abrasive member past the rotating commutator and under the pressure block, and friction means for hindering motion of said 25 block.

2. In a dynamo electric machine having a rotating commutator with high and low parts circumferentially in line, means for truing said commutator, comprising a pressure 30 member, a guiding and supporting member for said pressure member, actuating means for advancing said pressure member towards said commutator, means for yieldingly resisting movement of said pressure member in at 35 least one direction without corresponding assistance to movement in the opposite direction, in any one of a plurality of positions automatically attained, to the end that said pressure member either hurdles said low 40 parts or at least bears substantially less heavily on said low parts than on said high parts, a flexible abrasive member and means for passing said flexible abrasive member between said pressure member and said commutator. 45

3. In a device for truing a rotating commutator having high and low spots, an abrasive strip, means for positioning said strip so that a portion thereof contacts with said 50 commutator, means for feeding said strip so as to bring new portions of said strip into contact with said commutator, means for advancing said portions radially towards said commutator and asphalt means for delaying 55 said advance.

4. In a dynamo electric machine having a rotating commutator with high and low parts circumferentially in line, means for truing said commutator, comprising a pressure 60 member, a guiding and supporting member for said pressure member, a flexible abrasive member positioned against said commutator and under said pressure member, means for advancing said pressure member into contact with said abrasive member, means for 65

blocking said pressure member against retrograde movement (relative to said guiding and supporting member) due to the reaction thrust of said high part, means for passing said flexible abrasive member between said 70 pressure member and said commutator, the guiding and supporting member being adapted for slight structural yielding to permit the high part of said commutator to pass under the pressure member. 75

5. In a dynamo electric machine having a rotating commutator with high and low parts circumferentially in line, means for truing said commutator, comprising a pressure member comprising a flexible strip 80 forming an engaging part of said pressure member and adapted to conform under pressure to the curved surface of the commutator and span a circumferential portion thereof, a flexible abrasive member positioned between said pressure member and said commutator, means for advancing said pressure member and so pressing said abrasive member against said commutator, means located laterally of said pressure member for passing 85 said flexible abrasive member between said pressure member and said commutator. 90

6. In a dynamo electric machine having a rotating commutator with high and low parts, means for grinding said commutator, 95 comprising a flexible abrasive member positioned to engage said commutator, a pressure member adapted to press said flexible abrasive member into frictional engagement with said rotating commutator, the said 100 friction causing said flexible abrasive member to be drawn along past said rotating commutator, and means for limiting the movement of said flexible abrasive member to a speed substantially less than the surface 105 speed of said rotating commutator. 110

7. In a dynamo electric machine having a rotating commutator with high and low parts, a truing device comprising a flexible abrasive member, a spacing or pressure member positioned adjacent to the commutator and at a distance from the high part thereof somewhat less than the thickness of said flexible abrasive member, said flexible abrasive member being positioned under said pressure member and pressed thereby into frictional engagement with the high part of said rotating commutator, said frictional engagement with said rotating commutator causing said flexible abrasive member to be drawn 115 along past said rotating commutator, and means for limiting the rate of movement of said flexible abrasive member. 120

8. In a dynamo electric machine having a rotating commutator with high and low parts circumferentially in line, a truing device comprising a spacing block positioned adjacent to said commutator, a flexible abrasive member, means for yieldingly pressing said block towards said commutator, an 125 130

abutment limiting the advance of said block towards said commutator to a distance from the high part thereof somewhat less than the thickness of said flexible abrasive member, 5 said flexible abrasive member being positioned under said pressure member and pressed thereby into frictional engagement with the high part of said rotating commutator, said frictional engagement with said 10 rotating commutator causing said flexible abrasive member to be drawn along past said rotating commutator, at a rate of movement substantially less than the rate of movement of said commutator.

15 9. In a dynamo electric machine having a rotating irregular commutator with high and low parts circumferentially in line, means for truing said commutator comprising a pressure member, a flexible abrasive member, 20 positioned and adapted to be moved tangentially, under said pressure member, actuating means for advancing said pressure member toward said commutator, and means for resisting movement of the pressure member 25 in at least one direction without correspondingly assisting the movement in the opposite direction, whereby said pressure member presses substantially harder on the abrasive member when in registration with parts 30 of the commutator of relatively slight altitude than when in registration with the lower parts of the commutator.

10. In a dynamo electric machine having a rotating irregular commutator with high and low parts circumferentially in line, means for truing said commutator comprising a pressure member, a flexible abrasive member, 35 positioned and adapted to be moved tangentially, under said pressure member,

actuating means for advancing said pressure member toward said commutator, and means for frictionally resisting movement of the pressure member in at least one direction without correspondingly assisting the movement in the opposite direction, whereby said pressure member presses substantially harder on the abrasive member when in registration with parts of the commutator of relatively slight altitude than when in registration with the lower parts of the commutator. 70

11. In a dynamo electric machine having a rotating irregular commutator with high and low parts circumferentially in line, means for truing said commutator comprising a pressure member, a flexible abrasive member, positioned and adapted to be moved tangentially, under said pressure member, actuating means for advancing said pressure member toward said commutator, and delayed action means for slowing down movement of said pressure member whereby the pressure of said pressure member on said abrasive member is substantially greater when the abrasive member registers with the high part than when it registers with the low part. 75

12. In a device for truing a rotating commutator, an abrasive strip, means for positioning said strip so that a portion thereof contacts with the commutator, means for resisting retrograde movements of the strip with relatively great increase in resisting force with slight increase in retrograde displacement until a predetermined resisting force is exceeded and thereafter permitting substantial retrograde movement without substantial increase in resisting force. 80
